CARTON

Robert N. Eichorn, Endicott, N.Y., assignor to International Business Machines Corporation, New York, N.Y., a corporation of New York

Filed Dec. 20, 1957, Ser. No. 704,173

5 Claims. (Cl. 229—33)

This invention relates to improvements in cartons and more particularly to a variable length carton foldable from a one-piece blank adapted for retaining articles such as tabulating cards for card controlled business machines and the like.

Tabulating cards, or record cards as they are sometimes called, must be carefully packaged for shipment and storage in order to prevent damage to the cards in which case they would not be useful in operating the controlled machine.

Previous attempts have been made to provide an adequate carton for packaging these cards but these previous attempts have been rather unsuccessful and unsatisfactory. The paper stock used in the manufacture of tabulating cards is generally allowed to vary in thickness within certain tolerance limits and it is necessary to accommodate this variation in card thickness where a predetermined number of cards are to be packed within a carton. For example, if an acceptable tolerance is plus or minus 0.0004 inch and it is desired to have 2000 cards in all cartons, it is necessary to provide a carton which can accommodate the variance in length which would occur with the tolerances indicated (0.8 inch) in order to compactly contain the predetermined number of cards.

One solution to this problem would be to provide a carton having a capacity to contain a predetermined number of cards of the maximum tolerable thickness. Any variation below this maximum capacity could be accommodated by either putting in more cards or by filling up the void space with shim means. In either event, whether the carton is filled with extra cards or with shim means, the operation would be quite costly.

Another solution to the problem would be to provide a variable capacity carton, the capacity being varied by varying the length of the carton. In applicant's copending application Serial No. 656,022, filed April 30, 1957, there is disclosed a two-piece variable length carton for packing a predetermined number of record cards of varying thickness in which one of the two pieces is effectively attached to the other at varying points. However, this two piece carton, while solving the problem of variable length, requires two separate blanks which must be assembled in the variable length positions and it is more complex than the improved one-piece variable length carton of this invention.

Hence, it is a principal object of this invention to provide a one-piece variable length carton for retaining a stack of a predetermined number of articles, such as tabulating cards, which may have varying thickness.

Another object of this invention is to provide a variable capacity carton constructed from a one-piece blank which is easily and quickly assembled for filling and closure.

The requirements of a carton for packaging tabulating cards may differ depending on whether the cards are being shipped in the container or being retained in the container for file purposes. While the cards are being

2

shipped in the container, accessibility to the cards is of little importance and protection of the cards from damage is of major importance. When the carton is being held as a file, accessibility of the cards is of highest importance as well as protecting cards from damage. Accordingly, it is a still further object of this invention to provide a one-piece variable length container which gives maximum protection to the articles contained therein during shipment and provides easy accessibility to the articles during storage. In other words, it is an object of this invention to provide a variable capacity carton which can be readily packed and folded to any number of different lengths and can subsequently be used for storage and file purposes.

With these and other objects in view, the variable length one-piece carton of this invention contemplates providing a single blank foldable into a tray section having side walls and end walls. This tray section is adapted to contain the predetermined number of record cards packed therein. The blank also has an integral cover extension hingedly connected to the tray portion of the blank for providing a lid for the packaged cards. The hinged connection between the tray and the cover extension is of novel construction so that the cover extension may be hinged from a number of separate points on the end of the tray to provide the variable length of the tray and therefore of the covered carton.

Other objects and advantages of this invention will be apparent from the following detailed description taken in connection with the accompanying drawings wherein:

Fig. 1 is a perspective view of a preferred embodiment of the carton of this invention folded to its maximum length.

Fig. 2 is a perspective view of the carton folded to its maximum length with its cover raised showing the record cards contained therein.

Fig. 3 is a side elevation view of the carton folded to its minimum length, with the shadow lines showing the carton folded to its maximum length.

Fig. 4 is a perspective view of the carton partially folded to its maximum length.

Fig. 5 is a perspective view similar to a portion of Fig. 4 showing the carton being folded to its minimum length.

Fig. 6 is a sectional view taken along lines 6—6 of Fig. 8.

Fig. 7 is a plan view of the one-piece blank used in forming the carton.

Fig. 8 is a side sectional view of the carton folded to its minimum length.

Fig. 9 is a perspective view of the carton folded to a length intermediate the maximum and minimum lengths.

Referring to the drawings, the variable length carton comprises generally a tray portion 10, and integral cover extension 12 hinged to the tray portion by novel hinge means 14.

The carton may be constructed from a single blank 16 as shown in Figure 7. This blank is preferably scored longitudinally at 18 and 20 to provide upwardly foldable side walls 22 and 24 on each side of a bottom panel 26.

The blank 16 is crushed between lines 27, 28 and line 29 is heavily scored to insure that a front end wall 30 will be folded therealong. The front end wall has a score line 32 and a score line 34 providing an end wall extension panel 36. This panel is scored at 38 and 40 to provide end wall locking ears 42 and 44.

A suitable pull tab 45 may be created in the end wall 30 by a pair of cut portions 43.

The front end wall 30 is divided from the side panels by longitudinal cuts 46 and 48 and transverse cuts 50 and 52. These transverse cuts provide shoulders 54 and

56 on locking ears 42 and 44 for the purpose of locking the front end carton in its assembled position, as shown in Fig. 8. Suitable transverse score lines 58 and 60 substantially coextensive with the crushed area provide hinged side wall flaps 62 and 64 at the front end of the side walls 22 and 24. This entire front end construction is substantially identical with the end construction described in applicant's copending application for a two-piece variable length carton and reference may be had thereto for a more detailed description.

The side walls are also provided with end flaps 66 and 68 at the rear ends thereof. These flaps are provided with transverse score lines 67 and 69 dividing the flaps from the side walls proper.

The integral cover extension 12 comprises a center panel 70 having longitudinal score lines 72 and 74 along the edges thereof providing side walls 76 and 78. Corner flaps or ear portions 80 and 82 are hingedly connected to the end of the side walls nearest the hinge means 14 at the transverse score lines 84 and 85. These flaps 80 and 82, as will be explained hereinafter, function as locking ears for holding the back end of the carton together when the cover 12 is closed.

The integral hinge section of the blank joining the body panel 26 to the central cover panel 70 is divided by several transverse score lines, of which four lines 86, 87, 88 and 89 are shown in the illustrated embodiment. Score lines 86 and 88 provide the hinge means when the cover extension is folded to provide a minimum length tray, and score lines 87 and 89 provide the hinge means when the cover extension is folded to provide a maximum length tray. The side flaps 66 and 68 have transverse score lines 90 and 91 therein substantially coextensive with score line 87 which is the base score line of the maximum length tray. However, score lines 90 and 91 are set inwardly from score line 87 a distance equal to the thickness of the stock of the blank 16. Score lines 90 and 91 form the fold line for the flaps 66 and 68 instead of lines 67 and 69 when the blank is folded to its maximum length.

The side flaps 66 and 68 are separated from the hinge portion by longitudinal cut lines 92 and 93. The corner flaps or ears 80 and 82 of the cover sides 76 and 78 are also separated from the hinge portion by longitudinal cut lines 94 and 95. The cover side wall corner flaps 80 and 82 and the tray side wall corner flaps 66 and 68 are separated from each other by cuts 96 and 97.

When preparing a carton for filling, the side walls 22 and 24 of the blank may be folded upwardly and their end flaps 62, 64 folded inwardly, as shown in Fig. 4. Front end wall 30 is folded upwardly and the extension 36 is foldable 90° inwardly to a position parallel with the top of the side walls, after the locking ears 42 and 44 of the extension 36 have been folded inwardly 90°. The shoulders 54 and 56 of the ears 42 and 44 provide a locking means for locking the front end of the carton in its erected position. For a more detailed description of the erection of this end of the carton, reference may be had to applicant's copending application mentioned previously.

The cards are placed compactly in the carton starting the filling at end 30 and extending toward the rear end. If the thickness of the predetermined number of cards is at the minimum tolerance limits the carton must be folded to its minimum length to compactly hold the cards. This minimum length fold is shown in Fig. 5 wherein the side wall flaps 66 and 68 are foldable inwardly toward each other along score lines 67 and 69. The cover extension is foldable about score lines 86 and 88 and the cover extension corner flaps 80 and 82 are not folded at all but merely function as a continuation of the cover side walls 76 and 78.

When the predetermined number of cards to be packed in the carton are of maximum tolerance thickness, the carton must be folded to its maximum length as shown

in Fig. 4. In this case, the side wall flaps 66 and 68 are folded along score lines 90 and 91 inwardly toward each other. The cover extension is folded along score lines 87 and 89 and the cover extension side wall flaps 80 and 82 are folded outwardly to serve a locking or binding function and frictionally lock the cover in place when it is folded downwardly over the cards.

Whether the flaps 80 and 82 are in their folded or unfolded condition, according to the length of the carton, 10 they function to hold the end flaps 66 and 68 and the hinge portion 14 of the carton together when the cover 12 is closed. The flaps 80 and 82 also are referred to herein as "locking ears."

To prevent distortion of the end cards by the flaps 66 and 68, Fig. 4, a card-size pad of corrugated material (not shown, made from the same stock as the carton blank, may be interposed between these flaps and the end card of the stack.

When the length of the stack of a predetermined number of cards is in between the maximum and minimum limits, the carton is folded in the manner set out above but instead of folding on the maximum or minimum hinge lines the folds are made at lines between the maximum and minimum hinge lines at a point corresponding to the length of the stack of cards in the carton.

An important feature of the invention is the provision of the slits 94 and 95, Fig. 7, which enables the ear portions 80 and 82 to be folded back anywhere along the length of these two slits. In conjunction with this, of course, the flap portions 66 and 68 may be folded anywhere along the length of the slits 92 and 93 between the maximum and minimum lines, Fig. 7. Hence, any intermediate-length stack can be accommodated by (1) folding the flap portion 66 around the end of the stack, the fold being made somewhere between the lines 67 and 90, (2) similarly folding the flap portion 68 somewhere between the lines 69 and 91, (3) folding the bottom panel 26 at the proper place between the lines 86 and 87, (4) folding the top panel wherever necessary between the lines 88 and 89, (5) folding the ear portion 80 back at the necessary intermediate position between the lines 84 and 96 to give the requisite binding or locking action when the carton is assembled, and (6) folding the ear portion 82 back at the necessary intermediate position between the line 85 and cut edge 97 to give the requisite binding or locking action when the carton is assembled. A carton folded to an intermediate length is shown in Fig. 9.

The closure of the carton may be aided by a machine which may sense the end of the card stack containing a predetermined number of cards and fold the blank at the proper place, which may be any place in between the maximum and minimum limit fold lines depending on the length of the stack of the cards.

The carton may be utilized for storage or file purposes and in this instance the pull tab 45 may be used as a handle to pull the carton from its storage space.

After the carton has been emptied of its cards, one may desire to reuse the carton as a storage container. In this event the carton generally will be folded to its minimum length (Figs. 5 and 8) so that the cover panel 70 will extend the entire length of the carton. At the front end of the carton, instead of having the panel 36 (Figs. 1 and 2) extending over and partially obscuring the contents, one may fold the locking ears 42 and 44 in against the extension 36 and then fold this panel around the flaps 62 and 64 to hold them against the wall 30. This prevents the front of the carton from unfolding when it does not have the locking action of the card stack and the cover to hold it in place, as it would in normal use.

The score lines 90-91 and 67-69 located on flaps 66 and 68 may also serve as indicating means for the height or length of the stack of cards. In case the length 75 of a stack of a predetermined number of record cards ex-

tends beyond lines 90—91 the cards exceed the maximum allowable thickness, and if the length of the stack of cards does not extend to score lines 67—69 the cards are less than the minimum allowable thickness.

In practice, one may wish to provide the carton blank with only the minimum-length score lines, omitting the maximum-length score lines 84, 85, 87, 89, 90 and 91, Fig. 7. This is shown in Fig. 9 and is within the contemplated scope of the invention, the important feature of which is the provision of the slits 92, 93, 94 and 95 which are suitably disposed to permit folding the carton blank selectively throughout a range of effective lengths from minimum to maximum.

Applicant has shown and described a preferred embodiment of a variable length one-piece carton for packaging record cards and the like. The embodiment disclosed was for the purpose of illustration only and one skilled in the art may see variations which may be utilized. Therefore, applicant's invention is not limited by the disclosed embodiment but only by the spirit and scope of the appended claims wherein he is entitled to a reasonable range of equivalents.

I claim:

1. A variable length one-piece carton for a predetermined number of stacked card-like articles, such as tabulating cards, which may vary in thickness to cause variations in the length of the stack, the carton comprising a blank scored and cut to provide: a bottom panel, an end wall, a pair of side walls, a cover extension having a hinge portion connected with said bottom panel at the end thereof opposite said end wall and also having side portions adapted to fit inside said side walls when the carton is closed, and end flaps foldably connected to said side walls at the ends thereof nearest said hinge portion, said cover extension side portions terminating at their ends nearest said end flaps in locking ears for holding said end flaps and said hinge portion together when the carton is closed, each of said locking ears being constituted and arranged so that when the blank is flat said ear adjoins a part of said hinge portion but is separate from said hinge portion longitudinally of the carton blank for a distance commensurate with the range of variation in the length of the carton, whereby each locking ear is individually foldable against its respective cover extension side portions; said end flaps, hinge portion and locking ears being foldable selectively at any of a multiplicity of interrelated positions to provide variable length flaps, locking ears, bottom panel, cover extension and therefore a variable length carton to accommodate the variations in the length of the card stack enclosed thereby.

2. A carton as defined in claim 1 wherein said hinge

portion is selectively foldable on any of a multiplicity of pairs of spaced lines, each pair corresponding to a particular length of carton, said end flaps being foldable on a line substantially coextensive with the first line of the selected pair of lines, and said locking ears being foldable on a line substantially coextensive with the second line of the selected pair of lines whenever the length of the carton exceeds a predetermined minimum length.

3. A carton as defined in claim 2 wherein said locking ears are adapted to perform their function of holding said end flaps and hinge portion together while in an unfolded condition relative to their respective cover extension side portions when the carton blank is folded to provide a carton of said predetermined minimum length.

4. A variable-length carton adapted to be assembled from a one-piece blank comprising the following portions: a tray having a variable-length bottom panel, two side walls and an end wall; a cover extension member having a variable-length cover panel and two side walls, the latter being respectively adapted to fit inside said tray side walls when the carton is assembled; and an intermediate hinge portion connecting said tray bottom panel to said cover panel at the end of said tray opposite said end wall; said hinge portion being foldable at variable points to define variably positioned edge boundaries for said bottom panel and said cover panel according to the variable length of the carton, said tray side walls having integral end flap portions respectively juxtaposed to but separate from said hinge portion when the carton blank is flat and each being foldable at variable points commensurate with the location of said bottom panel edge boundary when the carton is assembled, and said cover side walls having integral locking ear portions respectively juxtaposed to but separate from said hinge portion when the carton blank is flat and each being foldable at any variable point commensurate with the location of said cover panel edge boundary when the carton is assembled to hold said end flaps and said hinge portion together.

5. A variable length carton as defined in claim 4 wherein said hinge portion initially has uniform resistance to bending throughout an area thereof where said variable fold points are located.
